COMPUTER SYSTEM

Richard L. Snyder, Jr., and Robert R. Goodrich,
Princeton, N. J., assignors to Radio Corporation
of America, a corporation of Delaware

Application December 27, 1943, Serial No. 515,842

8 Claims. (Cl. 315—9)

1

This invention relates to computer systems such as are utilized to derive the algebraic sum of a plurality of electrical pulses, and has for its principal object the provision of an improved system and method of operation whereby the sum of the applied pulses is indicated by the position of an electron beam irrespective of the polarity of the applied pulses.

The characteristic features of the invention are: (1) means for forming a pair of electron beams, (2) a pair of targets one of which has alternate strips of high and low secondary electron emissive material and the other of which consists of plates spaced slightly from one another, and (3) intercoupled deflectors for so controlling the movement of the two beams that one of them is moved in discrete steps across the target having alternate strips of high and low electron emissive material and in a direction dependent on the polarity of the applied pulses.

Additional objects of the invention are the provision of resistance means for intercoupling the different targets and beam deflectors, and the provision of targets which present different symmetrical patterns to the different beams.

The invention will be better understood from the following description considered in connection with the accompanying drawings and its scope is indicated by the appended claims.

Referring to the drawings:

Figure 1 is a wiring diagram of a computer system constructed in accordance with the invention, and

Figure 2 illustrates a constructional detail of Fig. 1.

The system of Fig. 1 includes a cathode ray device 10 (hereinafter called the control tube) and a cathode ray device 11 (hereinafter called the stepping or indicating tube).

The stepping tube 11 (in which the position of the electron beam indicates the algebraic sum of the applied pulses) includes an electron gun 12 for forming a beam of electrons, a target 13 having alternate areas 14 and 15 (see Fig. 2) of high and low secondary electron emissive material, a pair of deflectors 16 and 17 for moving the electron beam up and down along the target 13, and a pair of electrodes 18 and 19 for collecting the secondary electrons emitted by the areas 14 and 15 when they are struck by the electron beam. The low emissive areas may be of carbon and the high emissive areas may be aluminum. A source of potential 20 is provided for maintaining the collectors 18 and 19 at a predetermined positive potential and a power supply unit 21 and resistors

2

22 and 23 are provided for maintaining the electron guns of the devices 10 and 11 in operating condition.

Operation of device 11 is based on the well known principle that the net charge delivered to the target, and hence the current through the target coupling resistor, is dependent on the number of electrons in the beam striking the target and on the ratio of secondary emission in the region of bombardment. If the ratio is greater than unity and there is a positive collecting field present (in this case there is, it being provided by the two collectors 18 and 19) an excess of electrons leaves the target and the net current difference between the beam current and secondary current is supplied through the target resistor. A voltage therefore appears across this resistor making the target positive with respect to the source of target potential. If the beam strikes a region wherein the secondary emission ratio is less than unity, the net difference of current between the primary and secondary electrons supplied through the resistor is reversed and the potential of the target drops below that of the supply. If the beam is on a boundary between high and low secondary emission, it may be divided so that the net current on the high secondary emission side is equal to the net on the low secondary emission side and no resultant current flows in the resistor so the target potential is the same as that of the supply. This variation in potential of the target potential, as hereinafter explained, is utilized to influence the deflection of the beam in device 10.

The device 10 includes an electron gun 24 for forming a beam of electrons, a pair of electrodes 25 and 26 for deflecting the beam in a horizontal direction, a pair of electrodes 27 and 28 for deflecting the beam in a vertical direction and a target which consists of a back plate 29 and interconnected front plates 30 and 31 which are slightly spaced from the back plate 29. It will be noted that the back member 29 and the front members 30 and 31 are so arranged with respect to one another as to present to the control beam 40 a symmetrical pattern, this pattern being formed by the upper half of the member 29 and the member 30 and also by the member 31 and the exposed triangular area at the lower corner of the member 29. Which of these similar patterns is used depends on the polarity of the applied pulses.

The pulses to be counted are applied through a lead 32, a capacitor 33 and a resistor 34 to the horizontal deflector 25 of the device 10. They

are also applied through resistors 35 and 36 to the vertical deflector 27 of the device 10 which is connected through a lead 37 to the target 13 of the device 11. The interconnected front plates 30 and 31 of the target of the device 10 are grounded through a resistor 38 and are connected to the deflector 16 of the device 11. The back plate 29 is grounded through a resistor 39 and is connected to the deflector 17 of the device.

With these connections and with no pulse applied to the terminal 32, the beams of the devices are stabilized at the points indicated by the broken lines 40 and 41, the beam 40 being equally divided between the plates 29 and 31 and the beam 41 being equally divided between a high emissive area 14 and a low emissive area 15.

The application of a positive pulse to the terminal 32 moves the beam of the device 10 upward and to the left, the pulse being of sufficient potential to overpower the negative potential produced by movement of the beam of the device 11 onto a low emission area 15 of the target 13. As the beam 40 moves onto the back plate 29, the deflector 17 becomes more negative and the beam 41 is deflected to the next high emissive area, thereby making the potential of the target 13 more positive and facilitating the movement of the beam 40 to the front plate 30. As this plate 30 becomes more negative, the deflector 16 of the device 11 becomes more negative and the upward movement of the beam 41 is arrested.

Since the applied pulse is only great enough to start the control beam over the plate 29, the above condition (where the control beam 40 on the boundary between plates 29 and 30 and the stepping beam 41 rests on a boundary between the areas 14 and 15 with the high emissive area 14 above and the low emissive area 15 below) is stable so long as the applied pulse is near its maximum.

When the applied pulse subsides, however, the control beam 40 moves to the right and downward striking the plate 29, making the electrode 17 more negative and moving the stepping beam upward until it comes to rest at the next boundary between an area 14 and an area 15 with a low emissive area above and a high emissive area below. At the same time, the control beam 40 is moved downward across the plate 29 to its illustrated stable position on the boundary between the plates 29 and 31. Successive positive pulses applied to the terminal 32 thus operate to stabilize the stepping beam 41 at successive boundaries which have a low emissive area above and a high emissive area below.

The effect of a negative pulse applied to the terminal 32 is similar to that described above with the exception that: (1) the control beam 40 is driven downward and to the right until it reaches the boundary in the notch in the lower right hand corner of the plate 31, and (2) the beam 41 is stepped downwardly instead of upwardly as in the case of the positive pulse.

The invention thus affords a ready means of deriving the algebraic sum of a number of applied pulses irrespective of their polarity. It is apparent that the various parts of the devices 10 and 11 may be enclosed within a single envelope if desired and that the target 13 may have any desired number or arrangement of its high and low emissive areas.

We claim as our invention:

1. The combination of means for producing a first electron beam, a first target including members of different configuration slightly spaced

from one another, means for producing a second electron beam, a second target including alternate areas of low and high secondary electron emission, means maintained at a positive potential for collecting the electrons emitted from said areas, means for moving said first beam on said first target in response to the application of pulses to be counted, means responsive to said movement for moving said second beam across one pair of said alternate areas for each of said pulses, and means responsive to change in the potential of the second of said targets for modifying the movement of said first beam.

2. The combination of means for producing control and counting electron beams, a first target including back and front members spaced from one another and shaped to present a symmetrical pattern to said control beam, a second target having alternate areas of high and low secondary electron emission, means maintained at a positive potential for collecting secondary electrons emitted from said areas, means for moving said control beam from said front member to said back member in response to applied pulses, and means responsive to said movement for moving said counting beam across said areas.

3. The combination of means for producing control and counting electron beams, a first target including back and front members spaced from one another and shaped to present a symmetrical pattern to said control beam, a second target having alternate areas of high and low secondary electron emission, means maintained at a positive potential for collecting secondary electrons emitted from said areas, means for moving said control beam from said front member to said back member in response to applied pulses, and means responsive to said movement for moving said counting beam across said areas, and means responsive to electrons emitted from said areas for modifying the movement of said control beam so that said counting beam is moved across adjacent pairs of said areas in response to each of said pulses.

4. The combination of means for producing control and counting electron beams, a first target including back and front members spaced from one another and shaped to present a symmetrical pattern to said control beam, a second target having alternate areas of high and low secondary electron emission, means maintained at a positive potential for collecting secondary electrons emitted from said areas, means for moving said control beam from said front member to said back member in response to applied pulses, means responsive to said movement for moving said counting beam across said areas, and means responsive to the electrons emitted from said areas for continuing the movement of said control beam so that said counting beam is moved across said areas in one direction in response to positive pulses and in the opposite direction in response to negative pulses.

5. The combination of mean for producing control and counting electron beams, a first target including back and front members spaced from one another and shaped to present a symmetrical pattern to said control beam, a second target having alternate areas of high and low secondary electron emission, means maintained at a positive potential for collecting secondary electrons emitted from said areas, means for moving said control beam from said front member to said back member in response to applied pulses, means responsive to said movement for

moving said counting beam across one of said low emission areas to an adjacent high emissive area, and means responsive to electrons emitted from said adjacent high emissive area for continuing said movement to said front member.

6. The combination of means for producing first and second electron beams, a first target, means for applying pulses to be counted, means for moving the first of said beams on said first target in response to the application of said pulses, a second target having alternate areas of high and low secondary electron emission, and means controlled by said first beam to move said second beam by discrete steps from one to another of said high secondary electron emission areas and in a direction dependent on the polarity of said pulses.

7. The combination of means for producing first and second electron beams, a first target, means including separate pairs of deflectors for moving the first of said beams on said first target in a direction dependent on the polarity of pulses applied to said deflectors, a second target having alternate areas of high and low secondary electron emission, and means including a single pair of deflectors connected to said first target for moving said second beam by discrete steps from one to another of said high secondary electron emission areas in response to each of said pulses.

8. The combination of means for producing first and second electron beams, a first target, pairs of deflectors for moving said first beam on said first target in different directions, common means for applying pulses to said pairs of deflectors, a second target having alternate areas of high and low secondary electron emission, and means connected to said first target for moving said second beam on said second target by discrete steps from one to another of said high secondary electron emission areas and in a direction dependent on the polarity of said pulses.
